DESIGN FOR A NUT MEAT EXTRACTOR

Lester C. Wadsworth, Detroit, Mich.

Application July 29, 1940, Serial No. 94,005

Term of patent 14 years

To all whom it may concern:

Be it known that I, Lester C. Wadsworth, a citizen of the United States of America, residing at Detroit, in the county of Wayne and State of Michigan, have invented a new, original, and ornamental Design for a Nut Meat Extractor, of which the following is a specification, reference being had therein to the accompanying drawing, forming a part thereof, wherein:

I claim:

The ornamental design for a nut meat extractor, substantially as shown.

LESTER C. WADSWORTH.
